UNITED STATES PATENT OFFICE.

CHARLES OSEAN, OF WOODCLIFF, NEW JERSEY, ASSIGNOR TO NATIONAL CARBON COMPANY, INC., A CORPORATION OF NEW YORK.

FLASH LIGHT.

Application filed February 2, 1923. Serial No. 616,568.

This invention relates to focusing flashlights and particularly to means whereby the adjustable device which alters the focus and beam of a flashlight may be retained or locked in any particular position of adjustment.

Focusing flashlights, especially when carried about in tool kits, pockets, etc., are apt to get out of the focus for which they were adjusted. It is desirable in some cases to retain an exact focal adjustment and the principal object of this invention is therefore to provide a simple means for retaining the focusing device in any position of adjustment. More specifically, the invention aims to provide such a retaining or locking means for a type of focusing flashlight in which the focus is altered by the adjustment of the rear end cap, an example of which is shown and described in application Serial No. 466,639, filed May 20, 1921, in the name of Lee J. Voorhees.

The above and other objects and the novel features of the invention will be apparent from the following description taken in connection with the drawings, in which:

Fig. 1 is a central sectional view of a flashlight embodying this invention, and

Fig. 2 is an enlarged view of the improved locking means, showing the same partly in section and partly in elevation.

Broadly speaking, the object of the invention is attained by releasably locking the focusing device at any one of its positions of adjustment as by means of a metal locking ring that is adjustable along the flashlight casing into engagement with an adjustable end cap to retain the latter in any one of its numerous positions of adjustment.

Referring to Fig. 1, the invention is shown as applied to a well known type of flashlight that has a battery B which is in circuit with a lamp L disposed in front of a reflector A. The lamp and reflector are supported at one end of the flashlight casing C which has a cap K adjustably coupled to the rear end thereof.

The end cap K carries a metal shell D therein which engages the battery B, the other end of which abuts against the holder H that carries the lamp L. A spring P acts to keep the holder H always in engagement with the upper central terminal of the battery. By adjusting the cap K toward the left in Fig. 1, the holder H may be moved against the tension of the spring P to adjust the lamp L outwardly along the focal axis of the reflector, and the spring P will act to move the lamp L

and battery B inwardly when the cap K is adjusted in the opposite direction. The usual switch S and suitable conductors are provided to complete the circuit to light the lamp L.

In order to securely retain the end cap K in any one of its positions of adjustment and thereby prevent the accidental alteration of the focus and light beam of the flashlight, a locking ring R is concentrically mounted on the outside of the flashlight casing so as to be adjustable into and out of engagement with the cap K to clamp the same. In the particular arrangement disclosed the skirt or flange K' of the end cap is provided with a helical thread whereby it may be coupled to a similarly threaded portion at the rear end of the flashlight casing and may also be adjusted axially by rotating the cap. The flashlight casing C may be entirely of metal so that the necessary threads may be formed in the rear end thereof, or as shown, the body of the casing may be of fiber and a threaded metal fitting F may be secured thereto by rivets F'. The locking ring R, as illustrated, desirably consists of a tubular metal shell having a thread T extending inwardly from one edge adapted to interfit with the threads on the fitting F, so that by rotating the ring it will move axially along the fitting F toward and away from the edge of the flange K' that also interfits with threads on the fitting F. The other end of the locking ring R has a bead R' that projects slightly beyond the outline of the threaded part of the ring and provides a corresponding interior groove G into which the end of the flange K' projects when the locking ring is in clamping position. The outer surface of the bead R' and a portion of the cap K may be knurled to facilitate the adjustment of these parts. When the cap K is being adjusted to alter the beam from the lamp L, the ring R is out of engagement therewith, and after the desired beam is obtained, the ring is rotated to move it toward the edge of the flange K'. The open end N is of slightly greater diameter than the end of the flange K' so that the latter will bind against the fitting F when it is engaged by the camming surface G' of the locking ring. This tightening of the ring R also causes its forward edge to grip the flange K', preventing loosening of the cap and any accidental change of focus. If a change of focus is desired, the retaining ring R may be quickly loosened

whereupon the cap K may be rotated in either direction to obtain the desired focus, after which the ring R may be rotated to return it to its clamping position.

5 The improved ring is particularly advantageous because it may be readily applied to focusing flashlights now in use without any change in the construction of the latter. Minor changes in the construction of the ring 10 may be made without departing from the spirit of the invention or sacrificing any of its advantages.

I claim:—

1. A flashlight comprising the combination 15 of a lamp; a reflector; a battery in circuit with said lamp; a casing for said lamp, reflector and battery; an end cap adjustably coupled to said casing and carrying means engaging said battery to adjust the latter and 20 said lamp to vary the beam of the light therefrom, and a threaded ring adjustable on said casing to cooperate with said end cap and lock the latter in any desired adjusted position.

2. A flashlight comprising the combination 25 of a reflector; a lamp adjustable along the axis thereof; a battery in circuit with said lamp; a casing for said lamp, reflector and battery having a threaded portion at the rear end thereof; means for adjusting said

lamp along the reflector axis comprising a 30 rear end cap for said casing having a threaded flange coupling said cap to the threaded portion of said casing and permitting the axial adjustment of said cap; and means for securing said cap at any one of its adjusted 35 positions comprising an adjustable ring having a thread fitting the threaded portion of said casing and having a grooved portion receiving the edge of said flange and binding the latter against said casing. 40

3. The invention defined in claim 2 in which said grooved portion is of slightly greater diameter than said flange and is knurled on its exterior surface.

4. In a flashlight, the combination with a 45 lamp, a reflector, a battery in circuit with the lamp, and a casing for said lamp, reflector and battery; of a threaded member fast on the casing, adjusting means screwable along the threaded member for relatively adjusting 50 the lamp and the reflector, and a locking ring also screwable along the threaded member and effective simply by engaging with the peripheries of the threaded member and the adjusting means to lock the adjusting means in 55 any position desired.

In testimony whereof, I affix my signature.
CHARLES OSEAN.
